UNITED STATES PATENT OFFICE.

HILLARD J. POTTS, OF KANSAS CITY, MISSOURI.

ELECTRODE-HOLDER.

1,119,872.

Specification of Letters Patent.

Patented Dec. 8, 1914.

Application filed December 23, 1912. Serial No. 738,276.

To all whom it may concern:

Be it known that I, HILLARD J. Potts, a citizen of the United States, residing at Kansas City, in the county of Jackson, State of Missouri, have invented certain new and useful Improvements in Electrode-Holders; and I do hereby declare the following to be a full, clear, and exact description of the invention, such as will enable others skilled in the art to which it appertains to make and use the same.

This invention relates to electrode holders and has for an object to provide a device of this character which will hold different sizes of electrodes just as securely as the larger lengths of electrodes, and will be composed of a minimum number of simple parts that will not easily get out of order.

With the above objects in view the invention consists of certain novel details of construction and combination of parts herein-after fully described and claimed, it being understood that various modifications may be made in the minor details of construction within the scope of the appended claims.

In the accompanying drawing forming part of this specification: Figure 1 is a side elevation of the holder. Fig. 2 is an end elevation of the holder. Fig. 3 is a longitudinal sectional view through the holder. Fig. 4 is a cross sectional view taken on the line 4-4 Fig. 1.

Referring now to the drawing in which like characters of reference designate similar parts, 10 designates the body of the holder which is substantially triangular in cross section and is provided on the bottom with an attaching base 11. The holder is provided above the base with a laterally projecting lug 12 in which is formed a threaded opening 13 in which an adjusting screw 14 is disposed, this adjusting screw extending longitudinally of the holder and having the threads on one side mutilated to form a flat face 15 that extends longitudinally from end to end of the adjusting screw.

The lug 12 is terminally bifurcated to form hinge ears 16, and between these hinge ears a resilient clamp arm 17 is interposed, the clamp arm having the lower end curved abruptly inwardly as shown at 18 below the hinge ears and bearing terminally against the flat face 15 of the adjusting screw, while the upper end 19 of the arm is bent inwardly to overlie the tip of the adjusting screw and is terminally bent outwardly as shown at 20

to form a guide surface which facilitates insertion of the electrode 21 between the V-shaped inner face of the holder and the free end of the clamp arm. A retaining pin 22 is passed through alined openings 23 formed in the hinge ears and bears against the outer face of the clamp arm, this pin serving to bind the clamp arm against the adjusting screw and against the electrode. The clamp arm is formed with shoulders 24 on the side edges which engage with the top edges of the hinge ears and prevent gravitation of the clamp arm when the electrode is removed.

By virtue of the clamp arm bearing 70 tightly against the flat face of the adjusting screw, the latter will be prevented from accidental retrograde movement, while at the same time the adjusting screw may be manually advanced to move the electrode longitudinally beyond the end of the holder. Furthermore, by virtue of the clamp arm free end overhanging the tip of the adjusting screw, short lengths of electrodes may be inserted in the holder and will be securely held by the clamp arm regardless of whether the adjusting screw contacts with the electrode or not. All the figures show the electrode as partly consumed and the set screw in position to hold the electrode projecting 85 properly from the holder at this stage.

The attaching base 11 is beveled at the edges as shown at 24 and one corner is cut away as shown at 25 to facilitate entry of the base into the ordinary lamp clamp without 90 obstruction. A V-shaped notch 26 is formed at the tip of the spring to produce sharpened edges which penetrate and remove scale during rotation of the electrode.

What is claimed, is:—

1. An electrode holder including a body having an electrode receiving face, a lug projecting from said face, an electrode adjusting screw threaded through said lug, and an electrode leaf spring clamp held intermediate the ends by said lug and having one end overhanging the tip of said screw and having the other end abruptly bent toward and terminally contacting with said screw below said lug.

2. An electrode holder including a body, a lug projecting from said body, an adjusting screw threaded through said lug and extending longitudinally of said body, and having a flat longitudinal face, and an electrode leaf spring clamp held intermediate the ends by said lug and having one end

- overhanging the tip of said screw and having the other end bent toward and terminally contacting with said flat face below said lug.
3. An electrode holder including a body, a lug projecting from said body, an adjusting screw threaded through said lug and extending longitudinally of said body, an electrode leaf spring clamp held intermediate the ends loosely upon said lug and having one end overhanging the tip of said screw and having the opposite end bent toward and contacting with said screw below said lug, and means for normally holding said clamp against movement longitudinally of said body.
4. An electrode holder including a body,

a lug projecting from said body, an adjusting screw threaded through said lug and extending longitudinally of said body, said lug being terminally bifurcated to form ears, a pin carried by said ears, and an electrode leaf spring clamp confined between said ears by said pin and having one end overhanging the tip of said screw and having the opposite end terminally bent toward and contacting with said screw below said lug.

In testimony whereof, I affix my signature, in the presence of two witnesses.

HILLARD J. POTTS.
